ATTORNEY

UNITED STATES PATENT OFFICE.

FREDERICK WHARTON, OF NEW YORK, N. Y.

SWEATBAND FOR HATS.

Application filed July 11, 1925. Serial No. 42,949.

To all whom it may concern:

Be it known that I, FREDERICK WHARTON, a citizen of the United States, residing at New York, in the county of New York and 5 State of New York, have invented new and useful Improvements in Sweatbands for Hats, of which the following is a specification.

The object of this invention is to provide 10 a sweat band especially adapted to prevent pressure over the temples of the wearer of the hat to which the band is applied, in order to avoid loss of hair when due to lack of blood circulation under the scalp.

15 A further object is to provide a sweat band formed of a strip of material cut away in a particular and novel manner, so that the oppositely located notched portions will register with the edges of a somewhat wide 20 strip when folded over an intermediate portion thereof, this construction permitting the formation of a recess or the like at a point opposite each of the temples, so that pressure otherwise produced will be lessened, 25 or eliminated.

A further object is to provide a hat band with notches of different size on opposite edge portions, the band being folded along longitudinal parallel lines in such manner 30 that three thicknesses of material will be provided in the finished product, and an additional strip forming a part of the main strip will be available for the purpose of attaching the band to the hat.

35 With the foregoing and other objects in view, the invention consists in the novel features of construction, described, illustrated and claimed, it being understood that modification may be made within the scope 40 of claims without departing from the spirit of the invention.

In the drawings forming part of this application,

45 Figure 1 is a plan view looking from the under side of the brim of a hat, and showing my improved hat band applied thereto.

Figure 2 is a view in vertical section.

Figure 3 is a plan view of the blank strip from which the hat band is formed.

50 Figure 4 shows the strip folded to form a sweat band illustrated in section in Figure 2.

55 Figure 5 is a fragmentary view in vertical section showing a slightly modified form in which a filling or padding material is in-

serted into or between the layers of the sweat band.

In Figure 1 the brim of the hat is designated 10 and the crown is shown 12, and within the crown is the sweat band constructed in accordance with the present invention. The completed band comprises three thicknesses of material, as will be observed from an inspection of the cross section of Figure 2. The band as a whole is designated 14, and 60 is provided with recesses opposite each other and so positioned that they will be opposite the temples of the wearer of the hat, when the hat is in position for use.

The blank strip from which the sweat 70 band is formed is shown in detail in Figure 3 and this strip includes an intermediate or approximately central portion 16, a parallel portion 17, the parallelly extending portion 18 on the opposite side, and a narrow strip 75 19 serving to permit the proper attachment of the band within the crown, adjacent to the inner edge of the brim. Fold lines 21 divide the strip into the parallel portions indicated.

On one edge of the strip, deep notched 80 portions 23 are provided, and these terminate along the line 21 between sections 16 and 17. Opposite notched portions 23 are notched portions 24, the latter being of the 85 configuration shown, so that when the several portions of the strip are folded along the lines 21, to produce the complete device, the notched portions 23 and 24 will come into proper registration for forming recesses 90 or depressions 25, illustrated in Figure 4 and further shown in Figures 1 and 2. In order to secure this result the notched portions 23 may be formed of approximately 95 true U shape, while the notched portions 24 have a broad inner portion 24', and side edges 24'' which extend toward each other at the outer edge of longitudinally extending portion 18 of the band or strip.

When the band is to be formed from the blank illustrated in Figure 3, portion 18 is 100 first turned over the intermediate portion 16, and portion 17 is then folded over, so as to lie substantially parallel with portions 16 and 18. The extreme edge portion 19 is 105 folded over in the manner shown in Figure 2 and permits of securing the sweat band in position within the hat. It will thus be observed that a sufficiently stiff band is provided, but provision is made for reducing 110

or eliminating the pressure of the hat over the temples of the wearer.

In the form illustrated in Figure 5 the sweat band includes inner and outer thicknesses 30 and 31 and an intermediate layer of felt or the like 32, serving as a padding, the lower edge portion 19' corresponding in function with the portion 19 of the previous form.

10 Having thus described my invention, I claim:

1. A sweat band, comprising a strip of material having its edge portions notched, the notched edges of the strip being folded over an intermediate portion of the strip, with oppositely located notched portions in registration, to provide recessed portions opposite the temples of the wearer when the band is in position on a hat.

15 2. A sweat band, comprising a strip of

material having a continuous surface extending approximately centrally thereof, the strip including edge portions, one of which folds over the other and both of which fold over the central portion of the strip, oppositely located portions of the edges of the strip being notched, and the folded strip providing recesses by the registration of the notched portions.

20 3. A sweat band, comprising a strip of material having its edge portions notched, some of the notched portions being deeper than the others, the notched edges of the strip being folded over an intermediate portion of said strip, with oppositely located notched portions in registration, to provide recessed portions opposite the temples of the wearer when the band is in position on a hat.

25 In testimony whereof I affix my signature.

FREDERICK WHARTON.
